TUNABLE FREQUENCY SELECTIVE CIRCUITS

Robert Francis O'Neill, Chelmsford, and Joseph Douglas Brailsford, London, England, assignors to Radio Corporation of America, a corporation of Delaware

Application November 8, 1938, Serial No. 239,418
In Great Britain December 16, 1937

7 Claims. (Cl. 178—44)

This invention relates to tunable frequency selective circuits and though of wide application is primarily intended for the radio frequency signal selection circuits of broadcast and other radio receivers.

The usual requirement of the tuned circuits of a broadcast radio receiver is that there shall be a constant predetermined band pass width and a constant predetermined band pass characteristic curve shape suited to the prevailing general broadcast conditions—at present those imposed due to the adoption of a 9 kilocycle spacing between broadcast transmitters. Although these requirements can now be satisfied to a high degree as regards the intermediate frequency circuits of a superheterodyne receiver, for these circuits are, of course, of a fixed frequency which does not vary with tuning of the receiver as a whole, known variably tunable selection circuits such as are used in the radio frequency stages of a receiver, fall far short of the above requirements and vary undesirably in their characteristics as the receiver tuning is varied. The present invention enables the above requirements to be substantially satisfied as regards the variably tunable stages of a receiver. In known variably tunable signal pre-selection circuits of the band pass type both the width of the band passed and the degree of attenuation at a given frequency separation from the middle of the pass band, depend upon the tuning of the circuit, i. e., the frequency to which the middle of the pass band is adjusted, and an important object of the present invention is to avoid this defect.

According to this invention a variably tunable band pass selection filter of the type comprising a plurality of coupled resonant circuits is characterized by the use of mixed coupling between said circuits and the provision of means, uncontrolled with the variable tuning reactances of the filter, for varying the total effective resistance (including all losses, such as condenser dielectric losses, inductance eddy current losses and so forth) in each resonant circuit as the filter tuning is varied so that the ratio of inductance (L) to resistance (r) in each circuit varies according to a predetermined law with variation in tuning. In general the requirement will be constant band width and constant selec-

tivity and to satisfy this requirement the variation of resistance should be such that the ratio

$$\frac{L}{r}$$

remains constant. In special cases, however, other requirements may arise and these may be satisfied by suitably choosing the law of variation of

$$\frac{L}{r}$$

Preferably the required variation in resistance is obtained by providing, in association with each resonant circuit, a fixed resistance in series with a small variable control condenser of predetermined law of variation, this condenser being ganged controlled with the main tuning reactances of the filter. Where (the usual case) these reactances are condensers, the control condensers may most simply be provided in the form of one additional vane on each of the main tuning condensers.

The invention is illustrated in the accompanying drawing, wherein Fig. 1 shows one form of band pass filter in accordance with the invention; Fig. 2 shows a modification of the filter of Fig. 1; Fig. 3 is a constructional detail of a portion of the filter disclosed in Fig. 2; and Fig. 4 shows the equivalent electrical circuit of Fig. 3.

Referring to Figure 1 the band pass filter is constituted by a four terminal two wire-network having one input terminal 2 directly connected to one output terminal 4 to constitute one wire, the other wire containing in series in the order stated, between the remaining input terminal 1 and the remaining output terminal 3, a first inductance L_1 , a first resistance R_1 , a second resistance R_2 , and a second inductance L_2 . The two inductances L_1 , L_2 , are equal as also are the two resistances R_1 , R_2 . One of the two tuning reactances of the filter is constituted by a variable condenser C_1 connected between the input terminals 1, 2, and the other is constituted by a similar condenser C_2 between the output terminals 3, 4, these two condensers being ganged as indicated. The coupling branch of the filter is of the mixed or compound coupling type and consists of an inductance ML and a condenser CC in series in the order stated between the

junction point of the two resistances R_1 , R_2 , and the wire which connects terminals 2, 4. The inductance ML may be a separate coil but is preferably constituted, wholly or in part, by mutual inductance between the two inductances L_1 , L_2 . In accordance with this invention there is connected across each tuning condenser C_1 , C_2 , a fixed resistance RC_1 , RC_2 in series with a small variable control condenser VC_1 , VC_2 and these two control condensers VC_1 , VC_2 are ganged with the tuning condensers C_1 , C_2 , and are of such law of variation that the inductance-resistance ratio for the circuits of which they form parts remains substantially constant over the whole tuning range of the filter. Although, for the sake of simplicity the resistances R_1 , R_2 , are shown as separate resistance elements, in practice they will usually be constituted by the inherent resistances of the inductances L_1 , L_2 . The small variable control condensers VC_1 , VC_2 , are preferably constituted by a moving vane and a fixed vane additional to each of the main tuning condensers. The additional fixed vane is insulated from the main fixed vanes but the moving vane need not be insulated and can be of the same shape as the main condenser moving vanes. The additional fixed vane is connected to the main fixed vanes through a suitable fixed resistance which thus in effect constitutes the resistance RC_1 or RC_2 as the case may be and appears in effect as an addition to the main circuit resistance. The proportion of the total resistance which this additional part forms is dependent upon the size of the capacity between the auxiliary vanes (i. e., upon the capacity VC_1 or VC_2) and is therefore varied as the filter is tuned. More specifically the additional resistance which is thrown into the tuned circuit, by means of the auxiliary end vanes and the fixed resistance, is proportional to the square of the ratio of the auxiliary capacity to the main tuning capacity.

It is desirable that no resistance should be added at the highest frequency in the range, that is at the minimum setting of the tuning condenser. Also every effort should be made to make the main tuning capacity low at this point, so that in order to obtain a low ratio of auxiliary capacity to main capacity, the auxiliary capacity must be very small indeed. The fixed minimum of the auxiliary capacity which occurs in practice, sets a limit to the ratio of the capacities and this ratio is sufficient to introduce more resistance into the tuned circuit than is desirable at the minimum tuning condenser setting. It becomes desirable therefore to supplement the fixed resistance by a suitably designed shunt impedance such that the effective resistance is reduced at the highest frequencies. One suitable form of shunt impedance comprises a simple series circuit permanently tuned to the highest frequency though, of course, other types of shunting impedance could be employed for the same purpose. Figure 2 shows an embodiment like Figure 1 except that series tuned circuits TC_1 , TC_2 tuned, as just described, are connected across the resistances RC_1 , RC_2 while, in the said Figure 2, the capacities VC_1 , VC_2 are diagrammatically represented as constituted, as above described, by auxiliary vanes provided in the tuning condensers. To facilitate adjustment the auxiliary moving vanes may be segmented in the same way as that in which the normally provided end vanes of a present day ganged condenser unit are segmented

for the purposes of adjusting the individual condenser sections.

The provision of the additional vanes does not in any way introduce difficulty as regards ganging of condensers, for the usual segmented end vanes may be provided at the other ends of the individual condensers for this purpose. Thus, in the filter above described, the two tuning condensers could be constituted by two condenser sections in a ganged condenser unit having a single control shaft, each section having an adjustable segmented vane at each end. Two of these end vanes would be the normally provided ganging adjustment vanes and the other two would be the additional vanes provided by this invention.

Another and preferred way of overcoming any difficulty which may be experienced due to an undesirable high minimum capacity to earth of the auxiliary vanes consists in placing the said vanes, in each case, between two of the fixed vanes of the appropriate main tuning condenser. For example a thin layer of insulating material may be stuck to the face of a fixed vane of the appropriate main condenser and a layer of metal foil— this layer constitutes the auxiliary vane—stuck onto the insulating layer. Such an arrangement is illustrated in schematic section in Figure 3. Here FC_1 represents fixed vanes of the tuning condenser C_1 and MC_1 moving vanes thereof. On one of the fixed vanes FC_1 is stuck a layer IL of insulation and on this is stuck a layer of metal foil FVC_1 which thus constitutes the auxiliary vane for the condenser VC_1 and is positioned between two of the vanes FC_1 . The resistance RC_1 is connected as shown between FC_1 and FVC_1 , the vanes MC_1 being earthed. The equivalent electrical circuit is shown in Figure 4 in which K represents the capacity of the resistance RC_1 and of the auxiliary electrode FVC_1 with respect to the fixed vanes FC_1 . As will be appreciated, the resistance RC_1 will have no effect unless there is capacity from the foil FVC_1 to earth so that when the vanes MC_1 are moved out of interleaved position between vanes FC_1 , the resistance RC_1 is of substantially no effect. The capacity between FVC_1 and FC_1 merely shunts RC_1 . By suitably disposing or even shielding RC_1 its capacity may be also substantially wholly related to the fixed vanes FC_1 instead of to earth. The position of the moving vanes MC_1 thus controls the amount of additional resistance thrown into the circuit and by suitably shaping and disposing FVC_1 a desired law of resistance variation can be obtained. A similar arrangement is, of course, employed for C_2 , VC_2 and RC_2 .

The main advantages obtainable by means of the invention are:

- (1) Substantially constant performance over the tuning range;
- (2) No interference with the coils of the filter which can thus be designed to be of high Q value;
- (3) No appreciable extra loss introduced at the high frequency end of the tuning range;
- (4) No interference with ganging adjustments;
- (5) No sliding contacts;
- (6) Mechanical simplicity and cheapness of construction.

The arrangement of Figures 3 and 4 offers the advantages of extreme cheapness, ease of manipulation, avoidance of any necessity for fundamental mechanical modification of the tuning condensers, and maintenance of low minimum capacities for the tuning condensers.

The invention is not limited to the particular form of band pass filter described, but may be applied to other and more complex forms of filter networks, if required.

5 We claim:

1. A variably tunable band pass selection filter of the type comprising a plurality of coupled resonant circuits, characterised by the use of mixed coupling between said circuits and the 10 provision of means, uni-controlled with the variable tuning reactances of the filter, for varying the total effective resistance in each resonant circuit as the filter tuning is varied so that the ratio of inductance to resistance in each circuit 15 varies according to a predetermined law with variation in tuning, said variation in resistance being obtained by providing, in association with each resonant circuit, a fixed resistance in series with a small variable control condenser of predetermined law of variation, this condenser being gang controlled with the main tuning reactances of the filter.

2. A filter as claimed in claim 1 wherein the main tuning reactances are condensers and the 20 control condensers are in the form of additional vanes on the main tuning condensers.

3. A filter as claimed in claim 1 wherein the main tuning reactances are condensers and the control condensers are constituted by end vanes 25 of the main tuning condensers.

30 4. A filter as claimed in claim 1 wherein the main tuning reactances are condensers and the

control condensers are constituted by end vanes of the main tuning condensers and are positioned between fixed vanes of said tuning condensers.

5 5. A filter as claimed in claim 1 wherein the main tuning reactances are condensers and the control condensers are constituted by end vanes of the main tuning condensers and are positioned between fixed vanes of said tuning condensers, the additional vanes being in the form of metal 10 layers attached to insulating layers in turn attached to the faces of fixed vanes of the main tuning condensers.

6. A band-pass filter comprising a pair of similar tunable circuits, each comprising an inductance and a variable condenser, a series path connected in shunt across each tunable circuit, said path comprising a resistance and a small adjustable condenser, and means for simultaneously adjusting the tuning condensers and the small 15 adjustable condensers for varying the total effective resistance in each tunable circuit, such that the ratio of inductance to resistance remains substantially constant for obtaining substantially 20 constant band width and selectivity. 25

7. A band pass filter as defined in claim 6 wherein the resistance of the series path is shunted by a series tuned circuit tuned to the highest frequency to which the tunable circuits are capable of being tuned. 30
